Des. 227,308
Patented June 12, 1973

227,308

AIR CUSHION VEHICLE

Raymond Leslie Wheeler, Brovacum, Old Road, East
Cowes, Isle of Wight, England

Filed Sept. 8, 1971, Ser. No. 178,851

Term of patent 14 years

Int. Cl. D12—14

U.S. Cl. D71—1 M

FIG. 1

FIG. 2

FIG. 3

FIG. 4

FIG. 5

FIG. 1 is a perspective view of the air cushion vehicle embodying my design;

FIG. 2 is a top plan view thereof;

FIG. 3 is a front elevation thereof;

FIG. 4 is a side elevation thereof; and

FIG. 5 is a rear elevation thereof.

I claim:

The ornamental design for an air cushion vehicle, as shown.
